PIERRE LEDERLIN, OF CHEDDE, FRANCE.

ELECTROLYTIC MANUFACTURE OF CHLORATES AND PERCHLORATES.

SPECIFICATION forming part of Letters Patent No. 727,813, dated May 12, 1903.

Application filed July 11, 1902. Serial No. 115,240. (No specimens.)

To all whom it may concern:

Be it known that I, PIERRE LEDERLIN, a citizen of the Republic of France, and a resident of Chedde, Haute Savoie, France, have invented new and useful Improvements in or Relating to the Electrolytical Manufacture of Chlorates and Perchlorates, which invention is fully set forth in the following specification.

The present invention relates to a new electrolytic treatment of alkaline chlorids in a solution of water, with the object of obtaining corresponding chlorates of an extremely high electrochemical yield, almost equal to its theoretical figure.

I have observed that whenever a neutral solution (originally neutral) of alkaline chlorid is electrolyzed the gases which are given off by the electrolyte (a variable mixture of oxygen and hydrogen gas produced by the decomposition of water) possess a characteristic smell which indicates the presence of chlorin or of oxygenated or chlorinated components in the mixture. Chemical reagents, moreover, disclose precisely the presence of these bodies, and it is easy to completely absorb and to measure the amount of the chlorin by means of iodid of potassium. Moreover, I have observed that under the same conditions the liquid originally neutral gradually and rapidly becomes alkaline, after which at the end of a sufficiently long time the alkalinity is brought to a certain strength and remains constant. I have proved that the strength of the liquid in caustic alkali corresponds in every case to the total amount of chlorin given off with the gaseous products generated and that from the moment at which the alkaline strength becomes constant the disengagement of chlorin ceases. This being established, I have discovered that the diminution in the yield of chlorate produced during the electrolysis, which can always be observed, is solely due to the formation or appearance of liberated alkali in the body of the liquid. In order to explain clearly, I will cite the following examples, in which all the conditions besides those expressly indicated in each example are exactly the same from one experiment to the other, (température, density, and intensity of the current, volume, nature, forms, dimensions, and distance of the electrodes, &c.:)

First example: A solution of NaCl is elec-

trolyzed with an addition of thirteen grams of $Na_2Cr_2O_7$ per liter and constantly maintained red by the addition of diluted HCl, according to the indications of my Patent No. 693,035. Under these conditions the electrochemical yield of chlorate of sodium reaches, as shown in my Patent No. 693,035, 0.55 gram per ampere-hour, which would correspond to eighty-three per cent. of the theoretical product, (0.66 gram per ampere-hour,) and this indefinitely, provided that the produced chlorate is periodically removed by refrigerating the solution, and thus crystallizing the chlorate and that the NaCl which is transformed is replaced and the liquid maintained constantly red by the addition of diluted HCl, as indicated in the patent. If the addition of HCl is sufficiently maintained even, 0.61 gram can be obtained per ampere-hour. However, if in the course of the electrolysis five grams of NaOH per liter are added to the electrolyte, of which four grams are used to restore the bichromate to the state of neutral chromate, thus only leaving one gram of NaOH free per liter, the yield sinks and falls from this moment to 0.41 grams of sixty-two per cent. of the theoretical yield. When two grams of free NaOH are added, the yield falls to 0.37 grain, which is thirty-seven per cent of the theoretical yield. It can thus be seen that the yield decreases in proportion as the addition of alkali is increased.

Second example: If, on the contrary, a neutral solution of NaCl is electrolyzed, (without any addition of chromates or bichromates,) it will be observed that when the spontaneous increase in the strength of free alkali has become constant the electrochemical yield of chlorate has become very low and been found to be 0.34 gram per ampere-hour, which would be fifty-one per cent. of the theoretical yield; but if at this moment a quantity of diluted HCl is added sufficient to neutralize the quantity of free alkali which in this moment remains in the liquid and from this moment the liquid is constantly maintained non-alkaline by the addition of the HCl corresponding to the quantities of free alkali which tend to form the electrochemical yield becomes suddenly very high and remains indefinitely at about 0.55 gram, which would be eighty-three per cent. of the theoretical amount, and it

even rises to 0.65 gram, which corresponds to ninety-two percent of the theoretical value if the introduction of diluted HCl is continued sufficiently long.

5 Third example: On electrolyzing a solution of NaCl with a previous addition of one gram of NaOH per liter the electrochemical yield falls again below that which is obtained in starting with an originally neutral solution 10 (first part of Example 2 above) and falls to 0.33 gram corresponding to fifty per cent. of the theoretical amount. If the addition of NaOH amounts to two grams, the yield falls to 0.30 gram, corresponding to forty-five per cent. of 15 the theoretical amount.

These three examples show clearly the injurious effect on the yield of small quantities of free alkali in the electrolyte. Moreover, I have also proved that the decrease of the electrochemical yield coinciding with the appearance of free alkali in the liquid is by no means proportionate to the actual loss of gaseous chlorin corresponding to this quantity of free alkali. In fact, according to Example 20 25, given above, before any addition of acid one hundred and two grams of NaClO₃ were obtained in, for instance, three hundred ampere-hours, while the theoretical yield of NaClO₃ would be one hundred and ninety-eight grams. There is therefore a loss in the production of NaClO₃ of ninety-six grams, corresponding to forty-nine grams of NaCl. Therefore at the same time the total yield of Cl in the iodid-of-potassium tube is 3.5 30 35 grams, a quantity which represents only 5.8 grams of NaCl. The diminution of the yield of chlorate calculated in chlorid is thus much superior to the quantity of NaCl, corresponding to the chlorin given off by the electrolyte. On the contrary, upon adding HCl during the period of the process, according to Example 2, one hundred and eighty-three 40 45 grams of NaClO₃ are produced during a period of three hundred ampere-hours until the process stops, instead of one hundred and ninety-eight grams, (the theoretical amount.) There is therefore a fall in production of fifteen grams of NaClO₃, corresponding to 6.7 grams of NaCl. At the same time the iodid-tube 50 55 gives a total yield corresponding to 3.4 grams of chlorin, corresponding to 5.6 grams of NaCl. In this case the loss in chlorin liberated and calculated in chlorin corresponds to eighty-three per cent. of the quantity (calculated in chlorid) of which the yield in chlorate is reduced. Thus it is proved, first, that the fall in the yield in chlorate in the electrolysis of alkaline chlorids in a neutral solution is solely due to the spontaneous appearance of small quantities of liberated alkali in the electrolyte; second, that this appearance comes from the disappearance of small quantities of chlorin from the body of the electrolyte and carried off in a gaseous form with the other 60 65 gases coming from the electrolytic decomposition, (oxygen gas and, above all, hydrogen

gas;) third, that in this case there is no proportion between this fall and this loss in chlorin. Since then I have sought and discovered various means for preventing the production of 70 harmful alkaline, and consequently for attaining indefinitely a yield which comes as close as possible to the theoretical amount. A primary means already known consists in the use of bichromate of potassium or sodium 75 with that of diluted hydrochloric acid, as has been described and explained in my Patent No. 693,035. I have discovered that it is still possible to obtain indefinitely a very high yield by starting not with the bichromate, 80 but with the neutral chromate, provided that by convenient additions of dilute HCl the liquid is kept constant non-alkaline—that is to say, the liquid can remain yellow—provided that by the use of acid the formation of free 85 alkali is always prevented. The approximate proportions of the neutral chromate and saline electrolyte (chlorid solution) may be two grams of neutral chromate to twenty grams of the saline electrolyte. In this manner, as 90 shown in my Patent No. 693,035, I cause, owing to the acidity, the favorable property of chromic acid to entirely and continually compensate the cathodic reduction, which is one of the causes for the loss in the yield. Thus a 95 yield of 0.55 to 0.50 gram per ampere-hour is obtained with NaCl, corresponding to eighty-four per cent. of the theoretical yield, and thus by using indefinitely the same metal cathodes and the same liquids periodically 100 deprived of the chlorate produced and recharged with chlorids corresponding to the quantity of the produced chlorate, while with the neutral chromate without the use of acids under the above-defined conditions the yield 105 falls to thirty-six grams, corresponding at the most to fifty-five per cent. of the theoretical amount, and remains at that indefinitely.

The accompanying drawing shows a sectional view of an ordinary electrolyte-cell 110 which may be used in carrying out the process herein described, A being an anode, B a cathode, and C the vessel for containing the electrolyte in which the anode and cathode are submerged.

115 I claim—

A method for the manufacture at a high constant yield of chlorates and perchlorates by the electrolysis of a chlorid solution with the previous addition of a corresponding neutral chromate, consisting in maintaining the electrolyte during the electrolysis in a non-alkaline state by the addition of hydrochloric acid.

In testimony whereof I have signed this 125 specification in the presence of two subscribing witnesses.

PIERRE LEDERLIN.
